CLAIM

The ornamental design for a gun sight, as shown and described.

DESCRIPTION

FIG. 1 is a perspective view of a gun sight as seen from the left rear portion, showing my new design;
 FIG. 2 is a perspective view of a gun sight as seen from the front left portion, showing my new design;
 FIG. 3 is a top elevational view thereof;
 FIG. 4 is a front view thereof;
 FIG. 5 is a side view thereof;
 FIG. 6 is a rear view thereof;
 FIG. 7 is a bottom view thereof; and,
 FIG. 8 is a perspective view thereof shown mounted on a firearm, the firearm shown in broken lines are for illustrative purposes only and form no part of the claimed design.

UNITED STATES PATENT AND TRADEMARK OFFICE
CERTIFICATE OF CORRECTION

PATENT NO. : Des. 420,088

Page 1 of 2

DATED : February 1, 2000

INVENTOR(S) : Timothy J. Sheehan

It is certified that error appears in the above-identified patent and that said Letters Patent is hereby corrected as shown below:

Title page, in Description:

Delete the sentence "Figure 1 is a perspective view of an aperture sighting device, as seen from the left rear portion, showing my new design;"

Delete the sentence "Figure 2 is a perspective view of an aperture sighting device, as seen from the left front portion, showing my new design;" and insert "Figure 1 is a perspective view of a gun sight, as seen from the left front portion, showing my new design;" in its place.

Delete the sentence "Figure 3 is a top elevational view thereof;" and insert "Figure 2 is a top elevational view thereof;" in its place.

Delete the sentence "Figure 4 is a front view thereof;" and insert "Figure 3 is a front view thereof;" in its place.

Delete the sentence "Figure 5 is a side view thereof;" and insert "Figure 4 is a side view thereof;" in its place.

Delete the sentence "Figure 6 is a rear view thereof;" and insert "Figure 5 is a rear view thereof;" in its place.

Delete the sentence "Figure 7 is a bottom view thereof;" and insert "Figure 6 is a bottom view thereof;" in its place.
